Meyers, Bushman & Rea

UNITED STATES PATENT OFFICE.

GEORGE HOWLETT DAVIS, OF WEST ORANGE, NEW JERSEY.

PERFORATED ROLL FOR MUSICAL INSTRUMENTS.

1,312,520.

Specification of Letters Patent.

Patented Aug. 12, 1919.

Application filed December 6, 1916. Serial No. 135,379.

To all whom it may concern:

Be it known that GEORGE HOWLETT DAVIS, a citizen of the United States, residing at 35 Central avenue, West Orange, in the county of Essex and State of New Jersey, has invented certain new and useful Improvements in Perforated Rolls for Musical Instruments, of which the following is a specification.

10 This invention relates to improvements in music rolls, referring more particularly to means for protecting the perforated sheets when in rolled condition and for maintaining a substantially constant general appearance of the exposed surface of the rolled sheet regardless of conditions brought about by repeated handling of the roll.

While the rewinding operation of perforated sheets employed for controlling the 20 operations of mechanisms, such for instance as self-playing musical instruments, places the sheet in a rolled condition, the convolutions are more or less loosely rolled, and for purposes of protecting the roll and for housing it in its container, it is desirable to tighten the convolutions after the roll has been removed from the instrument.

This is generally accomplished by grasping the central portion of the exposed surface of the roll in one hand and rotating the spool in the proper direction with the other hand. During the rotating movement there is generally a slip action between the surface of the sheet and the hand grasping it, therefore not only producing a frictional, but also a wear effect on the outer convolution, resulting in soiling the exposed surface of the sheet, the friction required in obtaining the tight winding causing a transfer to the sheet 30 of any soiling matter, etc., which may be on the hand; or should the exposed surface of the sheet carry any fine dust, etc., the friction and moisture will set the dust on the sheet. As a result, the exposed surface of the roll, when the latter is used at successive 40 intervals, gradually becomes soiled, thus detracting from the general appearance of the roll.

This soiling effect may not be seriously 50 objectionable where it is produced under playing conditions in the home. It is, however, a serious factor for the dealer in rolls of this type. As a general rule the dealer is

called on to play a selection in advance of a sale, and where this is done a number of 55 times before a sale is completed, the successive roll tightening operations will produce the soiled appearance without in fact affecting the actual playing value of the roll, so that a customer will receive the impression 60 that the roll is not new but is second hand and will not accept it. As a result, the deterioration in value of the roll while in the dealer's stock, due simply to the use of the roll for demonstrating purposes, is a serious 65 problem for the dealer.

The present invention is designed to provide an arrangement, shown in the present instance, in the form of an end label for the sheet, for meeting these and other objectionable features. The label preferably is of greater wear-resisting qualities than the sheet. The invention is also designed to provide a label having a length greater than is sufficient to form a single roll convolution, 70 the label being preferably color treated, marked, or tinted to produce a surface effect and appearance somewhat simulating or resembling surface soiling or discoloration such as usually results from contact of the 75 hand with the roll during hand-rolling and tightening operations, said surface treatment rendering such soiling substantially unnoticeable. By this arrangement, the rolled convolutions may be drawn tight in 80 the usual manner without rendering the exposed surface unsightly, soiling action being ineffective to materially change the appearance of the exposed surface through the 85 tendency to neutralize the effect produced 90 by the soiling action.

The invention further contemplates the use of a label for sheets of this character, the label having a length sufficient to provide a plurality of convolutions, and carrying suitable matter which may be explanatory of or bearing on the subject matter of the composition or of its author, this matter being positioned on the label in such manner as to be protected by the outer convolution 95 100 and therefore free from the soiling action.

To these and other ends, the nature of which will be readily understood as the invention is hereinafter disclosed, said invention consists in the improved construction 105 and combination of parts hereafter fully

described, illustrated in the accompanying drawings, and more particularly pointed out in the appended claims.

In the drawing the figure shows a music sheet roll having the label secured thereto, the label and a portion of the roll being shown as unwound.

10 designates a music sheet spool carrying a perforated music sheet 11 of a well known 10 type.

12 indicates a label positioned at the end of the sheet, the label having the usual loop 13 to permit attachment to the take-up roll when the musical selection is to be played. 15 The label may be formed integral with the sheet, but I prefer to provide a separate label and secure it firmly to the free end of the sheet in suitable manner. By such arrangement the labels are not only of uniform 20 length, but the printing or other operations necessary to produce the arrangement presently described, are provided on a comparatively short flat element as compared with the length of a perforated sheet, which, during 25 such operations, would be partially wound on its spool and hence less readily handled. Furthermore, the separate label enables the use of material of greater wear-resisting qualities and strength, as for instance 30 a tougher fibrous material, than is generally employed in producing the perforated portion of the sheet. There is thus provided a sheet-enveloping element which protects the perforated portion of the sheet when 35 rolled, withstands the general wear more efficiently, while at the same time the connection between the label and perforated body portion aids in maintaining the integrity of the latter, especially at its outer end.

40 The label is preferably of equal width with the sheet body-portion, and has a length greater than the length of a single convolution, a preferred arrangement being to provide more than a single convolution, especially where the free end is tapered as shown in the drawing. In this way, at least one convolution is of the width of the body-portion, the tapered portion increasing the thickness of the protective covering at that 50 portion of the roll over which the tapered portion of the label is wound.

As before pointed out, it is the universal custom to tighten up the roll convolutions after the roll has been removed from the instrument, one hand grasping the roll intermediate the ends of the spool, the grasp being of the full-hand character. The friction between the hand and roll is such that any matter which may be carried by the hand in such form as to be readily transferred, will pass on to the exposed surface of the roll. Repeated operations of this kind soil the appearance of the surface, gradually giving the roll a somewhat unsightly appearance.

65 It would be impracticable, for various rea-

sons, to provide a structure of this character capable of being readily cleaned and hence, to meet the conditions, I produce an exposed surface which may receive the surface soiling as usual, but which is so arranged that the soiling is practically ineffective to change the general appearance of the wound roll, thus eliminating the marked contrast in color, etc., which the soiling action produces under present practice. In other words, I 70 produce a surface appearance of a character which somewhat simulates or resembles the surface soiling or discoloration which is produced under such conditions, thus meeting the objections by practically neutralizing the 75 detrimental soiling effect through making the soiling unnoticeable visually.

This result may be obtained in different ways, but I prefer to obtain the effect by marking or color tinting or treating the label 80 in such manner that at least that portion which forms the outer convolution will retain its appearance unaffected by the soiling action.

The tinting may take the effect of an 90 artistic design, thus adding to the attractiveness of the rolled sheet, or the markings or tinting may be more or less irregular in character. The tinting may be uniform or of a graduated or shading type, or entirely irregular. Or, if desired, and as is shown in the drawing, the markings or tinting may be a combination of these effects, a portion 95 of the label carrying a fanciful design *a* and a more or less regular tinted portion *a'*. The design *a* will be more or less covered by the taper convolution of the roll, thereby rendering it less liable to soiling effect, the portion *a'*, when the label is unwound, having the appearance of a background for the 100 design, this effect being retained even though the soiling action may actually change the appearance of portion *a'*, the *ensemble* effect remaining substantially the same regardless of the soiling action.

110 As shown, the label is of a length to form a plurality of convolutions and if desired, I may arrange the design with a space *a*² (entirely covered by the outer convolution or convolutions when the sheet is rolled) on 115 which suitable matter may be placed, as by printing. For instance, the space may contain the words of a song when the sheet carries perforations of a musical selection having words; or it may contain a brief historical or other statement bearing on the song or on the author of the selection. By reason of the particular location this matter remains unsoiled owing to the protection afforded by the covering convolution.

120 The label may also carry a space *a*³ to receive the title of the composition.

125 The preferred arrangement is to employ the separate label, which is of such dimensions, when secured to the sheet, as to pro- 130

vide one or more convolutions equal in width to the width of the sheet, the dimensions being such as will enable this result to be obtained, and, at the same time, produce an exposed surface free from superposed elements, such as would be provided in applying a label of smaller dimensions to the surface of the sheet, this being a common practice in the art, the label being pasted on to the sheet.

I thus avoid the disadvantage of attempting to tighten the convolutions of a roll having a small superposed surface at a point where the roll is grasped during the tightening operation.

As pointed out, the marking or tinting of the label or sheet, as the case may be, may be produced in various ways, the word "tinting" as employed herein, not being intended to limit the invention to a color scheme arrangement, but rather to indicate the production of a surface for effecting the result desired whether it be by embellishment or ornamentation or by markings regular or irregular in design, etc., so long as the general effect to be produced is obtained.

All music rolls carry indicia giving at least the name of the composition—to identify the particular roll—and such indicia is located at such point as will retain it exposed when the roll is wound, so that such indicia is subject to the same soiling conditions as the remainder of the exposed convolution. It will, therefore, be obvious that any attempt to neutralize the effects of the soiling would be practically useless if the soiling action on the indicia remain unneutralized. By the use of the type of neutralizing effects herein disclosed, soiling of the indicia is made unnoticeable by the fact that the soiling of the entire surface is neutralized by being rendered unnoticeable.

While the separate label effect is preferred, the invention is not limited in this respect, it contemplating forming the label as an integral part of the perforated sheet, a structure which may be preferred for some purposes.

While I have herein shown and described the preferred way of carrying the invention into effect, both as to structure and use, it will be readily understood that the same may be varied and modified to meet various exigencies of use and I desire to be understood as reserving the right to make any and all such changes or modifications therein as may be found necessary or desirable in so far as the same may fall within the spirit and scope of the invention as expressed in the accompanying claims.

What I claim is:

1. As a new article of manufacture, a perforated music sheet adapted to be rolled,

said sheet having its outer surface at the free end thereof color treated to produce an effect somewhat simulating surface soiling or discoloration such as usually results from contact of the hand with the roll during hand rolling and tightening operations, said color treatment rendering such soiling substantially unnoticeable.

2. As a new article of manufacture, a perforated music sheet adapted to be rolled and having its outer surface at the free end convolution artistically decorated to produce a color scheme effect that will render substantially unnoticeable the surface soiling that usually results when the sheet is repeatedly rolled in the hand.

3. As an improved article of manufacture, a perforated music roll the free end of which is coated with a coloring material so applied as to somewhat simulate and thus render substantially unnoticeable surface soiling such as is usually imparted to the roll by contact therewith of the hand during hand rolling and tightening operations.

4. As a new article of manufacture an end label adapted to be attached to the free end of a perforated music roll, said label having a width substantially equal to the width of the music sheet to which it is to be attached and a length sufficient to provide more than a single roll convolution, and said label having a portion of its outer surface color treated to produce an effect somewhat simulating surface soiling or discoloration such as usually results from contact of the hand with a music roll during hand rolling and tightening operations.

5. An end label for perforated music sheet rolls, said label having a width equal to the width of the music sheet to which it is to be attached and a length sufficient to provide a plurality of roll convolutions including the convolution forming the exposed surface of the wound portion of the roll, said label also having data bearing on the subject-matter of the musical composition, said data being located a sufficient distance from an end of the label to be covered by an outer convolution of the roll when the sheet and label are in wound condition, and said label having a portion of its outer surface color treated to produce an effect somewhat simulating surface soiling or discoloration such as usually results from contact of the hand with a music roll during hand rolling and tightening operations.

6. As a new article of manufacture, a label adapted to form the free end of a perforated music sheet and to be wound with the sheet to form a wound roll, said label having a length sufficient to produce the outer convolutions of the roll and also having a surface thereof artistically decorated to produce a color scheme effect somewhat simulating such surface soiling as usu-

ally results when the sheet is repeatedly rolled in the hand, thus rendering such surface soiling substantially unnoticeable.

7. As a new article of manufacture, a label
5 adapted to form the free end of a perforated
music sheet and to be wound with the sheet
to form a wound roll, said label having a
length sufficient to produce the outer con-
volutions of the roll and also having sur-
10 face markings to produce a surface appear-
ance somewhat simulating such surface soil-
ing as usually results when the sheet is re-

peatedly rolled in the hand, thus rendering
such surface soiling substantially unnoticed-
able, said markings being positioned on the 15
portion of the label forming such exposed
face, other portions of the label bearing em-
bellishments on underlying convolutions of
the roll.

In testimony whereof I affix my signature 20
in the presence of a witness.

G. HOWLETT DAVIS.
